UNITED STATES PATENT OFFICE.

CLARENCE D. PLATT, OF BRIDGEPORT, CONNECTICUT.

QUICK-BREAK SWITCH.

1,365,007.

Specification of Letters Patent. Patented Jan. 11, 1921.

Application filed May 12, 1919. Serial No. 296,315.

To all whom it may concern:

Be it known that I, CLARENCE D. PLATT, a citizen of the United States of America, residing at Bridgeport, Connecticut, have 5 invented a new and useful Quick-Break Switch, of which the following is a specification.

My present invention relates to switches of the so-called quick break type and one of 10 the primary objects of the invention is to provide a simple and easily assembled form of quick break connection between the movable switch element and the operating member therefor.

15 Briefly, the invention comprises a link construction between the operating member and the movable switch member, having a lost motion engagement at one end with one of said members and having a connection at its 20 opposite end with the other member, which is engageable with said member only in an abnormal relation of the parts, whereby the parts may be engaged in this abnormal relation and thereafter will remain properly 25 connected during operation of the switch. A spring is provided for imparting a snap movement to the movable switch element and this spring is usually and preferably connected between the operating member and 30 the connecting link.

In the accompanying drawing, I have illustrated the invention embodied in one of its practical commercial forms, but would have it understood that the same is susceptible 35 of various modifications and changes without departure from the true spirit and scope of the invention.

In said drawing:

Figure 1 is a plan view showing the invention applied to a so-called inclosed switch.

Fig. 2 is broken section of the same taken substantially on the plane of the line 2--2 of Fig. 1.

45 Fig. 3, is a similar view illustrating the manner in which the parts are assembled.

Fig. 4, is a broken perspective view of the cross bar and link.

The switch illustrated is of the knife blade 50 type, embodying a pair of switch blades 5 pivoted on hinge posts 6 for engaging relatively stationary contacts 7, said parts being all mounted on a suitable base 8.

The movable switch blades are connected

in parallelism by a cross bar 9, shown as a 55 relatively flat bar of insulating material. This cross bar at a point intermediate its ends is shown as provided with notches 10 in its opposite edges, leaving an intermediate reduced portion 11.

60

12 designates the operating member which in the present case is in the form of a rocking arm pivoted at 13 in the box 14 in which the switch is mounted. The pivot of the switch operating member is substantially 65 concentric with the hinge of the switch blades.

15 designates the link connecting the operating member with the movable switch element. In the present disclosure this link 70 is formed at one end with a longitudinal slot 16 receiving the operating arm and providing a lost motion connection between the arm and link, and at its opposite end with a bearing 17 having a narrow opening 18 75 through the edge of the link. The largest diameter of the open bearing is slightly greater than the reduced portion 11 of the cross bar, and the throat 18 opening into the bearing is slightly greater than the 80 thickness of the cross bar. The throat 18 is provided at the lower side of the link, so that the parts cannot become disengaged in the normal operation of the switch.

In assembling the parts, the operating 85 member is usually first mounted in the box and the switch is then secured in the bottom of the box. Engagement of the cross bar with the operating link may be effected, as indicated in Fig. 3, by partially opening the 90 switch and passing the cross bar flat-wise into the open bearing in the link and then turning the switch bodily down into its final position. The parts are thus engaged while in an abnormal position and upon being 95 brought into normal position interlock to form a firm connection.

19 designates the spring which imparts the final snap movement to the switch blades. This spring is shown connected at 100 one end with the operating arm and at its opposite end with an angularly turned lug 20 on the end of the operating link.

In opening the switch, as the handle is drawn back, the operating arm will first 105 move in the slot 16 to take up the lost motion and to place the quick break spring under tension. Thereafter in the continued

movement of the operating arm the switch blades will move in unison with the operating arm until approximately at the moment of "break" whereupon the spring will assert itself to snap the blades quickly out of engagement with the stationary contacts. The spring when connected with the open-bearing end of the link, as illustrated, has a tendency to twist the link on the cross bar. 5 This tendency is offset however by the engagement of portions of the link at opposite sides of the bearing therein in the notches 10 in the opposite edges of the link. The link is thus guided on the cross bar and 15 prevented from binding or interfering with the free action of the parts. If it should become necessary at any time to remove the switch, this can easily be done by simply reversing the operation described above, the 20 detachable connection between the link and movable switch element making this an easy matter, but at the same time providing a positive connection between the parts in their normal operating positions. 25 The freely rocking connection between the link 15 and the cross bar 9 insures smooth operation even if the pivot 13 of the operating member is considerably eccentric to the switch blade pivots. This construction also 30 allows considerable variation in regard to the assembling of the parts such as the placing of the switch in the box.

I claim:

1. In an electric switch, the combination 35 of pivoted switch blades, a cross bar connecting the same and provided with notches in its opposite edges, an operating member for said switch, a link having a lost motion engagement with said member at one end 40 and provided near its opposite end with an open bearing engageable over the notched portion of the cross bar, said link when thus engaged with the cross bar having portions fitting in the notches in the opposite sides 45 of the cross bar so as to be guided thereby, and a spring connected between the operating member and the opposite end portion of the link.

2. The combination of a switch box, an 50 operating crank pivotally carried thereby and having a cross bar, a switch unit including an insulating base, switch contacts carried by said base, hinged blades carried by said base and adapted to co-act with said 55 contacts, a cross bar connecting said blades, a link connected to one of said cross bars, and means of connection between said link and the other cross bar permitting said link to be connected to said cross bar by a manual 60 operation when the switch unit is being inserted into said box and preventing disconnection of the link from said cross bar when the switch unit is secured in its normal operative position in the box.

3. The combination of a switch box, an

operating crank pivotally carried thereby and having a cross bar, a switch unit including an insulating base, switch contacts carried by said base, hinged blades carried by said base and adapted to co-act with said 70 contacts, a cross bar connecting said blades, a link connected to one of said cross bars, means of connection between said link and the other cross bar permitting said link to be connected to said cross bar by a manual 75 operation when the switch unit is being inserted into said box and preventing disconnection of the link from said cross bar when the switch unit is secured in its normal operative position in the box, and a spring connecting said link with one of said cross bars. 80

4. In an inclosed switch, a box, a switch operating crank secured to said box, a link connecting part within the box and mounted on said operating crank, a switch consisting of a base, contacts, blades and a cross bar connecting said blades, and interengaging means appurtenant to said link connecting part and said cross bar whereby the said link and cross bar may be operably connected 85 when engaged in an abnormal position and will be prevented from disengagement when the switch is secured in the box in a normally operable position.

5. The combination of a switch box, an 90 operating crank pivotally carried thereby, a switch unit including an insulating base, switch contacts, and a hinged blade all mounted on the insulating base, a link having a loose connection with the operating 100 crank, and special means of connection between said link and said switch blade, permitting said switch blade to be connected to said link by a manual operation in the act of inserting the switch unit in the box, and 105 preventing disconnection of the link from the switch blade when the switch unit is secured in place in the box.

6. In an electric switch, the combination 110 of pivoted switch blades, a cross bar connecting the same and provided with notches in its opposite edges, an operating member for the pivoted switch blades, and a link connected at one end with said operating member and provided near its opposite end 115 with an open bearing engageable over the notched portion of the cross bar and said link when thus engaged with the cross bar having portions fitting in the notches in the opposite sides of the cross bar so as to be 120 guided thereby.

7. In an electric switch, the combination 125 of pivoted switch blades, a cross bar connecting the same, and having a portion of elongated cross-section, an operating member for said switch, a link loosely connected to said operating member, and provided at its opposite end with a bearing slot having a contracted entrance adapted to receive the elongated section of the cross bar, and means 130

for preventing lateral displacement of said link on said cross bar.

8. In an electric switch, the combination of pivoted switch blades, a cross bar connecting the same, and having a portion of elongated cross-section, an operating member for said switch, a link loosely connected to said operating member, and provided at its op-

posite end with a bearing slot having a contracted entrance adapted to receive the elongated section of the cross bar, and means for preventing lateral displacement of said link on said cross bar, and a spring connecting said operating member and said link. 10

CLARENCE D. PLATT.
